NICHOLAS M. MICHAILOVSKY, OF BRONX, NEW YORK, ASSIGNOR, BY DIRECT AND MESNE ASSIGNMENTS, OF THIRTY-SEVEN AND ONE-HALF PER CENT TO PAUL NOEL RITTER, OF DOUGLAS MANOR, LONG ISLAND, NEW YORK, AND TWENTY-FIVE PER CENT TO HENRY W. BOETTGER, OF NEW YORK, N. Y.

DRIVING UNIT FOR LOUD-SPEAKERS

Application filed August 23, 1928. Serial No. 301,525.

This invention relates to the driving units or motors used for operating loud speakers, and the objects of the invention are to provide a device of this character, which will be of simple, inexpensive construction and highly efficient in its operation.

The novel features of the invention by which the foregoing and other desirable objects are attained will be clear from the following specification in conjunction with the drawing accompanying and forming part of the same.

In the drawing, Fig. 1 is a face view or side elevation of an embodiment of the invention and Fig. 2 is a lower end view of the same, the transmission connections in both views being broken, for lack of space.

The magnet employed in the present illustration is of the permanent horseshoe type as indicated at 3 and is provided at opposite faces of the same with the pole pieces 4 and 5 secured in place by the through screws 6 and spaced to provide the magnetic gaps 7.

The armature cooperating with the magnet is disclosed as a flat magnetic bar 8 pivotally supported intermediate its ends on a pin 8' carried by a bridge 9, which is secured to the ends of the yoke by screws 10.

For magnetizing the armature, two interconnected coils 11, 12 are shown surrounding the end portions of the armature and held flat against the inside cheeks of the pole pieces by being seated in recesses 13 in the opposite faces of the bridge.

To gain a maximum degree of interaction between the armature and pole pieces, the armature is shown as of approximately the same width as the magnetic gaps and as working freely without contact in notches 14 in the ends of the pole tips, which are but slightly wider than the thickness of the adjacent portions of the armature.

With this construction, it will be seen that the magnetic flux across the gap will be concentrated at the corners of the notches and the adjoining corners of the substantially rectangular flat armature and that therefore a maximum interaction between armature and pole pieces will be accomplished with the armature in the intermediate or starting posi-

tion shown and that this action will be continued as the armature rocks in one position or the other further into the notches. The tapering of the pole pieces down to the notched ends, as indicated in Fig. 1 aids in this concentration of the flux at the notch corners.

The movement of the armature may be imparted to the cone, diaphragm or other element by suitable transmission connections such as the rod 15 shown secured to one end of the armature and having an extension link 16 connected therewith. If desired, this transmission connection may be taken off from a point intermediate the support 8' and the end of the armature so as to gain a certain leverage effect.

The construction it will be observed is particularly simple and the parts may be mounted by the simple act of assemblage. The clearance between the armature and the notched portions of the pole pieces is relatively close and remains constant because of the parallel motion of the armature into the notches.

The thin flat form of armature shown is particularly light and sensitive, with but little inertia so that it responds quickly and truly to the incoming impulses. The structure as a whole is compact and takes up but little space for the work it accomplishes. To hold the armature so that it will at all times work truly in the slots or notches 14, the armature pin or support 8' may be supported at both ends, as indicated in Fig. 1, where the upper end of the pin is shown as having an anchorage or bearing in the raised or trussed like portion 9' of the bridge.

The magnet may be of electromagnetic as well as of the permanent type shown, and if found desirable, may be of the single pole instead of the bi-polar type shown.

What is claimed is:

1. A device of the character disclosed, comprising a magnet structure having a pole piece with a parallel sided notch in the end of the same, an armature mounted for movement in the direction of extent of said parallel sided notch and having a parallel sided portion operating with small clearance with

in said notch, a coil for magnetizing said armature and a power transmission connection extending from said armature.

2. Apparatus of the character disclosed, comprising a magnet structure having opposed polar projections with aligned parallel sided notches in the opposing edges of the same, an armature mounted for movement in the direction of extent of said notches and having parallel sided portions of a size and positioned to operate with small clearance in the notches and a magnetizing coil for said armature and a power transmission connection engaged with said armature.

15 3. A driving unit for loud speakers or the like, comprising a magnet yoke, pairs of opposed cooperating pole pieces at opposite faces of said magnet yoke and providing magnetic gaps at opposite sides of the magnet structure, the adjacent opposing ends of each pair of cooperating pole pieces having opposed notches therein, an armature supported intermediate its ends for movement in the plane of said notches and having portions of a size to operate freely in said notches and a magnetizing coil for said armature.

4. A driving unit for loud speakers or the like, comprising a magnet structure having opposed notched pole pieces, an armature mounted to operate in the direction of extent of the notches in said pole pieces and having a portion of less width, parallel with and moving in the notched portions of said pole pieces, a magnetizing coil for said armature and a power transmission connection engaged with the armature.

5. A driving unit for speakers or the like, comprising a magnet structure having a tapered polar projection with a parallel sided notch in the end of the same, an armature mounted for movement in the direction of extent of said parallel sided notch, said armature having a substantially rectangular portion of less width than the notch and mounted with the corner edges of the same opposite to the corner edges of the notch in the polar projections, a magnetizing coil for the armature and a power transmission connection extending from the armature.

50 6. A driving unit for speakers or the like, comprising a magnet structure having opposed pole pieces spaced to provide a magnetic gap and tapered in width down to said gap, the tapered ends of said pole pieces having inwardly extending notches therein, an armature mounted for movement between said pole pieces in the direction of extent of said notches and constructed for free movement in the notches, a power transmission connection engaged with said armature and a magnetizing coil for the armature.

7. A driving unit for speakers or the like, comprising a magnet yoke, pole pieces applied to opposite faces and providing magnetic gaps at opposite sides of the yoke, said pole pieces

being tapered down to said magnetic gaps and having notches in the tapered ends of the same, an armature mounted for movement in said gaps in the direction of extent of said notches and constructed for operation in the notches, a power transmission connection engaged with the armature and means for magnetizing the armature.

20 8. A construction as in claim 7, in which the magnetizing means includes coils surrounding the opposite end portions of the armature and a non-magnetic bridge across the ends of the yoke supporting said coils and the armature.

10 9. A driving unit for speakers or the like, comprising a magnet yoke, pole pieces at opposite faces and providing magnetic gaps at opposite sides of said magnet yoke, said pole pieces being tapered down to said magnetic gaps and having parallel sided notches in the opposing edges thereof, an armature having flat portions to freely enter said notches, the flat portions of said armature being of approximately the width of said gaps and the armature being mounted with the corner edges of said flat portions in opposition to the corner edges of the notches in the pole pieces, a power transmission connection engaged with the armature, magnetizing coils surrounding the end portions of the armature and means for supporting said coils and said armature in the relations described, said means enabling movement of the armature parallel with the notches in the pole pieces.

100 10. A driving unit for speakers or the like, comprising a magnet yoke, a bridge member secured across the ends of said yoke and having a trussed up portion, a support held at its opposite ends by the main portion and the trussed up portion of the bridge, an armature carried by the intermediate portion of said support between the main portion and trussed portions, a magnetizing coil for said armature, a power transmission element connected with said armature and pole pieces at the sides of the yoke and between which the trussed portion of the bridge is located.

In testimony whereof I affix my signature.
